ADVERTISING LAUNDRY CARDBOARD

Humberto Llach and Pedro R. Avalo, New York,
N. Y., assignors to Neway Advertising Corp.,
New York, N. Y., a corporation of New York

Application December 24, 1937, Serial No. 181,523

7 Claims. (Cl. 40—61)

This invention relates to new and useful improvements in advertising laundry cardboards.

More specifically the invention proposes the construction of a laundry board, for holding a pressed shirt or other pressed article, imprinted on one or both of its faces with advertising matter.

Still further the invention proposes the construction of a board having an element which 10 will arouse one's interest, in a certain portion of the advertising matter imprinted upon the cardboard.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a laundry cardboard constructed according to this invention.

Fig. 2 is a perspective view of the laundry cardboard.

Fig. 3 is a view similar to Fig. 1, but illustrating a different position of the parts.

Fig. 4 is an enlarged sectional view taken on the line 4—4 of Fig. 3.

Fig. 5 is an enlarged sectional view taken on the line 5—5 of Fig. 1.

The advertising laundry cardboard, according to this invention, comprises a laundry board section 10 for holding a pressed shirt or other article, and having advertising material 11 imprinted upon one of the faces thereof. The cardboard 10 is of conventional construction as is in common use for insertion into or upon pressed shirts when it is desired to fold them for delivery 35 to a customer. When the customer removes the shirt from the cardboard 10 the advertising matter will be brought into full view. A laundry board section 10' is pivotally connected at its upper end with the upper end of the section 10. 40 The section 10' is provided with a plurality of perforations 12, in its lower left-hand corner, dividing off a coupon 13'.

A means is associated with the cardboard section 10 for arousing the interest of the customer 50 to certain portions of the advertising material 11. This means comprises a continuous band 15 which encircles the body of the card 10 and which is slidably mounted thereon. A means is provided for urging this band 15 away from the interesting portion of the advertising mat-

ter and consists of a plurality of elastic bands 16 which have one of their ends 16^a fixedly attached to the body portion of the cardboard 10, and the other of their ends 16^b fixedly attached to a portion of the band 15.

Aligned openings 17 are in the band 15 and the body 10 of the cardboard and a soft cotter pin or similar pin 20 is passed through these openings. This pin is adapted to have its ends 20^a bent over after being inserted into the openings 17 to prevent it from becoming accidentally displaced therefrom. When the head of the pin 20 is gripped between one's fingers it may be withdrawn from the openings 17 permitting the rubber bands 16 to move the slide 15 away from 15 over the interesting portion of the board.

When the slide 15 moves away it will be noted that it exposes the bottom corner of the cardboard 10 which is provided with an auxiliary layer 21 which has three of its edges fixedly attached to the body of the cardboard 10 and which has its free edge adjacent one of the edges of the board 10. This auxiliary member 21 has a window opening 22 through which the contents thereof may be viewed.

A post card 23 is inserted into the open end of the envelope formed by the auxiliary member 21 and is adapted to be withdrawn therefrom for the purpose of returning it to the person or firm advertising on the laundry board 10 for receiving additional information concerning the article or service advertised thereon. In other respects this form of the invention is similar to the previous forms.

While we have illustrated and described the 35 preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. An advertising laundry cardboard comprising 45 a board, an element of the interest on said board, a member movably mounted on said board and normally covering said element, means for releasably holding said member fixed on said board, and resilient means for continually urging said member to a position removed from said element.

2. An advertising laundry cardboard comprising 50 a board, an element of interest on said board, a member movably mounted on said board and 55

- normally covering said element, means for releasably holding said member fixed on said board, and resilient means for continually urging said member to a position removed from said element, said element of interest comprising a card inserted into an envelope formed by an auxiliary member having three of its edges fixedly attached to said board with its free edge adjacent one edge of said board. 5
- 10 3. An advertising laundry cardboard comprising a board, an element of interest on said board, a member movably mounted on said board and normally covering said element, means for releasably holding said member fixed on said board, and resilient means for continually urging said member to a position removed from said element, said movably mounted member on said board comprising a continuous band engaging around said board. 15
- 15 4. An advertising laundry cardboard comprising a board, an element of interest on said board, a member movably mounted on said board and normally covering said element, means for releasably holding said member fixed on said board, and resilient means for continually urging said member to a position removed from said element, said movably mounted member on said board comprising a continuous band engaging around said board. 20
- 20 5. An advertising laundry cardboard comprising a board, an element of interest on said board, a member movably mounted on said board and normally covering said element, means for releasably holding said member fixed on said board, and resilient means for continually urging said member to a position removed from said element, said movably mounted member on said board comprising a continuous band engaging around said board, said means for releasably holding said member in a fixed position on said board comprising a pin engaging through aligned openings in said band and said board for restraining the action of said resilient means until said pin is removed from said openings. 25
- 25 6. In an advertising laundry cardboard, a board, a pocket formed in one corner of said board, an element of interest inserted into said pocket and viewable through a front opening formed in said pocket, and means for covering said opening to hide said element of interest and arouse one's interest. 30
- 30 7. In an advertising laundry cardboard, a board, a pocket formed in one corner of said board, an element of interest inserted into said pocket and viewable through a front opening formed in said pocket, and means for covering said opening to hide said element of interest and arouse one's interest, means for holding said means fixed in a position extended across said opening, and means for urging said first-mentioned means away from said opening to expose the same when said second-mentioned means is 35 released.
